CLAIM

The ornamental design for a tire, as shown and described.

DESCRIPTION

FIG. 1 is a perspective view of a tire, showing our new design;

FIG. 2 is a front elevation view thereof, it being understood that the tread pattern is repeated throughout the circumference of the tire;

FIG. 3 is a rear elevation view thereof;

FIG. 4 is a left side elevation view thereof, with the right side view being identical thereof;

FIG. 5 is an enlarged front elevation view of FIG. 2, showing a portion thereof; and,

FIG. 6 is an enlarged perspective view of FIG. 1, showing a portion thereof.

The portions depicted in broken lines of uneven length define the unclaimed boundary of the claimed design. The portions depicted in broken dashed lines illustrate portions of the tire that form no part of the claimed design.
